UNITED STATES PATENT OFFICE.

HARRY M. HAMRICK, OF PHILADELPHIA, PENNSYLVANIA, ASSIGNOR TO THE INTERNATIONAL INCANDESCENT LIGHT COMPANY, OF WEST VIRGINIA.

DESIGN FOR A CASING FOR AIR AND OIL SUPPLY FOR BURNERS.

SPECIFICATION forming part of Design No. 30,028, dated January 17, 1899.

Application filed December 21, 1898. Serial No. 699,962. Term of patent 3½ years.

To all whom it may concern:

Be it known that I, HARRY M. HAMRICK, a citizen of the United States, residing in the city and county of Philadelphia, State of Pennsylvania, have invented and produced a new and original Design for a Casing for Air and Oil Supply for Burners, of which the following is a specification, reference being had to the accompanying drawings, forming part thereof.

The leading feature of my design for a casing for an air and oil supply for a lamp-burner is a body formed of chambered sections extending in reversed directions from each other.

Figure 1 represents a side elevation of a casing for an air and oil supply for a lamp-burner embodying my design. Fig. 2 represents a vertical sectional view of Fig. 1.

Referring to the drawings, A designates the body of the casing, the same consisting of the chambered portions or sections B C, placed back to back and extending in opposite directions therefrom in reverse order.

D designates the tube of the burner, the same passing through said body.

Having thus described my invention, what I claim as new, and desire to secure by Letters Patent, is—

The design for a casing for air and oil supply to burners substantially as described and shown.

HARRY M. HAMRICK.
